(57) **CLAIM**

The ornamental design for a tricycle having a canopy, handle and mud guard, as shown and described.

DESCRIPTION

The nature and intended use of the article in which the design is embodied is that of a tricycle for children and the like, having a canopy, handle and mud guard.

FIG. 1 is a perspective view of a tricycle having a canopy, handle and mud guard showing my new design;

FIG. 2 is a top view thereof;

FIG. 3 is a side view thereof;

FIG. 4 is a front view thereof; and,

FIG. 5 is a rear view thereof.
